UNITED STATES PATENT OFFICE

147,560

DESIGN FOR A WINDOW REGULATOR
HANDLE

Henry T. King, Detroit, Mich.

Application December 29, 1945, Serial No. 125,109

Term of patent 7 years

(Cl. D10—8)

To all whom it may concern:

Be it known that I, Henry T. King, a citizen of the United States and a resident of 18467 Santa Rosa, in the city of Detroit, county of Wayne, and State of Michigan, have invented a new, original, and ornamental Design for Window Regulator Handle, of which the following is a specification, reference being had to the accompanying drawing, forming part thereof, in which:

Fig. 1 is a front elevational view of the window regulator handle showing my new design;

Fig. 2 is a top plan view of the same; and

Fig. 3 is an end elevational view thereof viewed from the right end of Fig. 1.

The characteristic features of my design are shown in the full lines in the drawing.

I claim:

The ornamental design for a window regulator handle, substantially as shown and described.

HENRY T. KING.
